UNITED STATES PATENT OFFICE.

JOB W. BLACKHAM, OF BROOKLYN, NEW YORK.

DESIGN FOR SKIRTS.

Specification forming part of Design No. 7,707, dated August 18, 1874; application filed July 16, 1874.
[Term of Patent 7 years.]

To all whom it may concern:

Be it known that I, JOB W. BLACKHAM, of Brooklyn, Kings county, in the State of New York, have invented a Design for Skirts, of which the following is a specification:

The nature of my design is fully represented in the accompanying drawings, to which reference is made.

A represents the body of the skirt, in scarlet or other attractive hue. B B are heavy cross-stripes, preferably black, or some heavy shade, forming a decided contrast with the ground-work, and also with the narrow lines of decoration C C, which appear to lie thereon. The heavy cross-bands B, with the top decoration C, are straight, but stand in a diverging position, gradually increasing their distance apart, and inclosing larger areas of the ground-work A as they approach the lower edge of the skirt. M are light isolated marks and dots, laid upon the ground-work A, and arranged, as shown, just within the borders of the areas inclosed between the several cross-bars B. D D are narrower cross-bands, and E are lines of dots or analogous decoration, appearing as laid upon the bands D. These decorative plaid figures may extend up the skirt as far as is necessary. At the upper edge they terminate in points I, having reverse points or notches J. Above the points I are oblique rows of separate flowers P, extending along parallel to the edges of the banded portion. On or opposite every alternate scallop H is a foliate ornament, L. Touches of light decoration appear on both the flowers P and tripartite foliage L.

The divergent positions of the cross-bands B and E, with the corresponding gradual

change of form of the inclosed areas, from the top to the bottom of the plaid, corresponds to the peculiar form of a skirt, and allows each line of approximately square or diamond figures to extend continuously around the approximately conical form.

The pattern or design may be varied in form and size, and in the precise arrangement of the details, so long as they form essentially the same design, and produce the same ornamental and distinctive effect.

In the drawing, Figure 1 represents a small portion on a large scale, while Fig. 2 shows the gradually-diverging lines and changed forms of the plaid figures, by showing more of the skirt on a small scale.

I claim as my design for a skirt—

1. The squares A, isolated border ornaments M, heavy cross-bands B, and light decoration C, as shown and described.

2. The narrow cross-bands D, with their light decoration E, in combination with the heavy bands B and their decorations C, as shown and described.

3. The foliate and floral ornaments L P, matched in the notched edges of the cross-banded portion A B, as shown and described.

4. The combination and arrangement of all the within decorative devices B C D E L M N P, as shown and described.

In testimony whereof I have hereunto set my hand this 10th day of July 1874, in the presence of two subscribing witnesses.

JOB W. BLACKHAM.
